US00D779454S

(12) **United States Design Patent** (10) Patent No.: **US D779,454 S**
(45) Date of Patent: ** Feb. 21, 2017

(54) **USER INTERFACE FOR WELDER**

(71) Applicant: **Lincoln Global, Inc.**, City of Industry, CA (US)

(72) Inventors: **Samuel Paul Crescenze**, Massillon, OH (US); **Ivan Paul Gracic**, Highland Heights, OH (US); **Jason Karl Leach**, Cleveland Heights, OH (US)

(73) Assignee: **Lincoln Global, Inc.**, City of Industry, CA (US)

(**) Term: **15 Years**

(21) Appl. No.: **29/545,716**

(22) Filed: **Nov. 16, 2015**

(51) LOC (10) Cl. **15-09**

(52) U.S. Cl.

USPC **D14/144**

(58) **Field of Classification Search**

USPC D15/144, 144.1, 144.2

See application file for complete search history.

OTHER PUBLICATIONS

Design application drawings submitted in U.S. Appl. No. 29/514,436, filed Jan. 13, 2015.

Primary Examiner — Patricia Palasik

(74) Attorney, Agent, or Firm — Brad C. Spencer

(57) **CLAIM**

The ornamental design for a user interface for welder, as shown and described.

DESCRIPTION

FIG. 1 is a front isometric view of a welder with the user interface layout showing our new design; FIG. 2 is a rear isometric view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top view thereof; FIG. 8 is a bottom view thereof; and, FIG. 9 is a detail view the user interface layout. The broken lines shown in the drawings illustrate portions that form no part of the claimed design.

1 Claim, 7 Drawing Sheets
